ADJUSTABLE BED LAMP

Clifford R. Myre, Paynesville, Minn.

Application April 27, 1949, Serial No. 89,955

5 Claims. (Cl. 5—92)

1

My invention relates to improvements in bed lamps for beds of the type commonly used in hospitals and which have an adjustably tilttable back-rest by means of which the occupant of the bed may be propped up from a fully prone position into various positions more or less approximating an upright sitting posture.

The invention contemplates the mounting of a bed lamp on a bed frame or other support adjacent thereto for movement of the lamp into various positions corresponding with the various positions into which the back-rest of the bed may be tilted, whereby the lamp may be properly located relative to the patient for his or her reading comfort or treatment in whatever posture he or she may be supported by said back-rest.

The invention further contemplates the interposition between the lamp mounting and tilttable back-rest of means adapted to shift the lamp mounting when the back-rest is tilted and thereby automatically locate the lamp in best suited relationship to the patient's altered position.

It is an object of my invention to provide a simple, durable and relatively inexpensive structure adapted efficiently to accomplish the ends above stated.

Other objects of the invention reside in the novel combination and arrangement of parts and in the details of construction hereinafter illustrated and/or described.

Briefly, the herein disclosed embodiment of my invention includes a tubular guide supported at the head of a bed having a tilttable back-rest. A plunger-like lamp mounting slidable in said tubular guide carries a lamp at an end thereof projecting beyond the tubular guide. One end of a flexible conduit is attached to said tubular guide in continuation thereof. In continuation of the other end of the flexible conduit is a tubular coupling, the extremity of which is pivotally connected with the back-rest of the bed at a point substantially removed from the pivotal axis thereof. Said tubular coupling has a slot therein extending longitudinally thereof and this slot slidably receives an anchoring post which is fixed to a stationary part of the bed. A push-pull wire within the tubular guide and the tubular element formed by said coupling and flexible conduit is connected at one end to the slidable lamp mounting and at its other end to said anchoring post, the arrangement and coaction of said parts being such that the lamp mounting is retracted relative to its guide when the back-rest of the bed is in a lowered flatwise position.

Upward tilting movement of said back-rest from said flatwise disposition thereof advances the lamp-mounting in its guide and downward tilting movement of the back-rest from a raised position retracts said lamp-mounting in said guide. Thus, the lamp on the lamp-mounting is automatically shifted to accord with the adjustment of the back-rest, thereby to best suit the lighting needs of the patient supported by said back-rest.

In the drawings, Fig. 1 is a side elevational view of a bed lamp embodying my invention and applied to a bed of the type having a tilttable back-rest; Fig. 2 is a fragmentary view, similar to Fig. 1, but showing a different relationship of the parts; Fig. 3 is a detail view partly in elevation and partly in section showing particularly the lamp-mounting and its guide; Fig. 4 is a detail view partly in elevation and partly in section showing particularly the coupling member associated with the bed structure; Fig. 5 is a sectional view in detail taken as on line 5—5 of Fig. 4 and Fig. 6 is a fragmentary side elevational view, similar to Fig. 1, showing the tubular guide of the bed lamp structure mounted on a stand adjacent the end frame at the head of the bed.

Reference being had to the drawing, it will be seen that I have shown in Fig. 1 a bed A of well known construction, the same being of the type commonly employed in hospitals and having a tilttable back-rest 10 embodied in the usual mattress-supporting element 11, which is carried on rails 12 supported by end frames 13, 14 at the head and foot, respectively, of the bed. The back-rests in such beds are tilted in different ways to adjust the same and they are secured in their various tilted positions of adjustment in various manners, all well known to those familiar with the art. In the present drawings, I have shown more or less diagrammatically a linkage system 15 of a kind commonly operated by a crank (not shown) located at the foot of the bed for adjustably tilting the back-rest forwardly and upwardly and for reversely tilting said back-rest rearwardly and downwardly. Fig. 2 shows the back-rest 10 at its lower rearward limit of movement flatwise of the bed in parallelism with the rails 12, and Fig. 1 shows said back-rest 10 at its upper forward limit of movement approximating an upright position.

The illustrated embodiment of my invention in lamp structures for beds of the type aforesaid includes a support or guide 16 of tubular formation intermediately of which is an outstanding stud 17 terminating in a ball 18. A bracket 19

consisting of mating members 20 held together with a clamping screw 21 provides a socket 22 in which the ball terminal 18 of the stud 17 is received and releasably gripped, said mating members 20 being provided with jaw portions 23 adapted to grip the top rail 13^a of the end frame 13 of the bed adjacent the back-rest 10, or any other suitable supporting structure similarly disposed relative to said back-rest 10. Such other suitable supporting structure for the bracket 19 and the guide 16 carried thereby may, for example, consist of a movable stand X including a base 39, a post 40 upstanding from said base, and an arm 41 extending horizontally from said post 40, said arm 41 being adapted to occupy a position adjacent the top rail 13^a of the end frame 13 of the bed and adapted to be embraced by the mating members 20 of the bracket 19 in the same manner that the top rail 13^a of the bed is shown to be embraced by said mating members 20 in Figs. 1 and 3 of the drawing. Thus, the support or guide 16 will occupy an elevated position and, within a normal range of angular adjustment universally, will extend generally lengthwise of the bed and upwardly pointed toward the front thereof.

Slidable within the guide 16 is a plunger-like mounting 24 the forward end of which projects from the forward end of said guide 16. A lamp socket 25 secured to said projecting end of said mounting 16 is supplied with an electric lamp 26 and is fitted with slackened wires 27 for electrically connecting the same with any convenient outlet supplying electric current.

Motion transmitting means operated by the back-rest 10 of the bed A upon the tilting of said back-rest from one position of adjustment to another are supplied to move the mounting 24 in the guide 16. Said motion transmitting means functions to advance the mounting 24 in said guide 16, causing the lamp 26 to be carried forwardly and upwardly in correspondence with the movement of back-rest 10 as it is tilted forwardly and upwardly. When said back-rest 10 is reversely tilted rearwardly and downwardly, said motion transmitting means functions to retract the mounting 24 in said guide 16, causing the lamp 26 to be carried rearwardly and downwardly in accord with such movement of said back-rest. This shifting of the lamp 26 in accord with the shifting of the back-rest 10 presents the light of the lamp 26 in position relative to the back-rest 10 wherein such light is best suited to the needs of the person supported by said back-rest, or to the needs of an attendant treating such person. Said motion transmitting means includes a tubular element B and a push-pull wire 28 slidable therein, said element B consisting of a flexible conduit 29 and a tubular coupling 30. One end of said conduit 29 is connected with the rear end of the tubular guide 16 in continuation thereof and the corresponding end of the push-pull wire 28 is socketed in and secured to the butt end of the mounting 24 as by means of a pin 31. One end of the tubular coupling 30 is connected with the other end of said flexible conduit 29 in continuation thereof. The opposite end of said tubular coupling 30 is pivotally connected with a side frame member 10^a of the back-rest 10 by means of a pivot pin 32 spaced a substantial distance from the pivotal axis 33 of said back-rest 10. Along its inner side, the tubular coupling 30 is formed with a slot 34 longitudinally thereof. This slot 34 slidably receives the end

of a binding or anchoring post 35 screwed into the rail 12 of the bed A. Said post 35 is formed with an aperture 36 transversely thereof which receives the end of the push-pull wire 28 within said tubular coupling. A set screw 37 threaded endwise into said anchoring post 35 engages the push-pull wire 28 in the aperture 36 in said post clamping said wire to the post. An access opening 38 in the tubular coupling 30 opposite said slot 34 therein enables said set screw 37 to be reached with a screw driver or similar tool from the outer side of said coupling 30. The tubular coupling 30 depends from the back-rest 10 and the flexible conduit 29 bows downwardly from the lower end of said coupling thence upwardly to the tubular guide 16.

The various parts hereinbefore described are proportioned and arranged so that the lamp 26 is fully retracted rearwardly and downwardly at the head of the bed A when the back-rest 10 is swung rearwardly and downwardly into a position flatwise of the bed as seen in Fig. 2. Upward forward tilting of the back-rest 10 from this flatwise position into a raised position more or less approaching an upright position, as shown in Fig. 1, decreases the length of the tubular element B between the anchoring post 35 and the guide 16 with the result that the push-pull wire 28 is caused by the flexible conduit 29 to advance the mounting 24 in the guide 16, such advancement of said mounting depending upon the extent to which the back-rest 10 is tilted upwardly and forwardly. Conversely, the length of said tubular element B between said anchoring post 35 and guide 16 is increased as the back-rest 10 is swung downwardly and rearwardly, the result being that the mounting 24 is retracted in the guide 16, the extent of its retraction depending upon the extent to which said back-rest 10 is tilted downwardly and rearwardly. Said movement of the lamp-carrying mounting 24 relative to the tilting of the back-rest 10 may be accomplished by omitting the tubular coupling 30 and substituting therefor an arm projecting forwardly from the bed-rest 10 beyond the pivotal axis 33 thereof. In such case, the flexible conduit 29 will be anchored to the bed rail 12 and the push-pull wire 28 will be attached to the free end of such forwardly projecting arm. However, the illustrated construction is preferred by reason of its simplicity of application to a bed and for the further reason that the tubular coupling 30 serves to prevent the buckling of that portion of the push-pull wire 28 projecting from the flexible conduit 29.

From the foregoing it will be understood that I have provided an exceedingly simple, durable and efficient bed lamp structure for beds of the type having a tiltably adjustable back-rest, such structure operating automatically to shift the lamp in relation to the shifting of the back-rest of such bed, whereby the light from the lamp is best suited to the needs of the occupant of the bed or his or her attendant in whatever position the occupant may be supported by the back-rest of the bed.

Changes in the specific form of my invention, as herein described, may be made within the scope of what is claimed without departing from the spirit of my invention.

Having described my invention, what I claim as new and desire to protect by Letters Patent is:

1. An adjustable lamp structure for a bed hav-

ing a tiltably adjustable back-rest, an end frame adjacent thereto and a stationary part beneath said back-rest, said structure comprising a tubular guide, means for universally adjustably supporting said guide on the end frame of the bed in an overhead position extending generally lengthwise of the bed, a plunger-like mounting slidable in said tubular guide and projecting at its forward end from the forward end of said tubular guide, a lamp carried by said mounting at its said forward end, a tubular element including a flexible conduit connected at one end thereof with said tubular guide at its rear end in continuation thereof and a tubular coupling adapted to be pivotally attached at one end thereof to the back-rest of the bed in a depending position, said coupling being attached at its other end to the other end of said conduit and constituting an extension thereof, said coupling having therein a slot longitudinally thereof, an anchoring post adapted to be secured to said stationary part of the bed and slidably received in said slot in said coupling, and a push-pull wire contained within said tubular guide, flexible conduit and coupling, one end of said wire being connected with said mounting at the rear end thereof and the other end of said wire being adapted to be connected with said anchoring post, the distance measured along the axis of said tubular element between said anchoring post and guide varying with movement of the back-rest when the lamp structure is connected for use, whereby, upon the upward tilting of the back-rest, the mounting is caused to be advanced in said guide and, upon the downward tilting of said back-rest, said mounting is caused to be retracted in said guide.

2. An adjustable lamp structure for a bed having a back-rest adjustably tilttable upwardly and forwardly and reversely tilttable downwardly and rearwardly and having also a stationary part adjacent said back-rest, said structure comprising a support adapted to be located adjacent the bed, a mounting supported by said support for movement generally lengthwise of the bed above the back-rest, a lamp carried by said mounting, a tubular element including a flexible conduit connected with said support and a tubular coupling connected with said conduit in continuation thereof, said coupling being adapted to be pivotally attached to said back-rest and having therein a slot longitudinally thereof, an anchoring post adapted to be secured to said stationary part of the bed and slidably received in said slot in said coupling, and a push-pull wire contained within said tubular element, one end of said wire being connected with said mounting and the other end thereof being adapted to be connected with said anchoring post, the distance measured along the axis of said tubular element between said anchoring post and support varying with movement of the back-rest when the lamp structure is applied to the bed for use, whereby, upon the upward and forward tilting of the back-rest, the mounting is caused to be moved forwardly with the back-rest and, upon the downward and rearward tilting of the back-rest, the mounting is caused to be moved rearwardly with said back-rest.

3. An adjustable lamp structure for a bed having a tiltably adjustable back-rest and a station-

ary part adjacent said back-rest said structure comprising a support adapted to be located adjacent the bed, a mounting movably supported by said support, a lamp carried by said mounting, a tubular element including a flexible conduit connected with said support and a tubular coupling connected with said conduit in continuation thereof, said coupling being adapted to be pivotally attached to said back-rest and having therein a slot longitudinally thereof, an anchoring post adapted to be secured to said stationary part of the bed and slidably received in said slot in said coupling, and a push-pull wire contained within said tubular element, one end of said wire being connected with said mounting and the other end thereof being adapted to be connected with said anchoring post, the distance measured along the axis of said tubular element between said anchoring post and support varying with movement of the back-rest when the lamp structure is applied to the bed for use, whereby, upon the tilting of the back-rest, the push-pull wire will cause said mounting to be shifted in one direction when the back-rest is raised and will cause said mounting to be shifted in a reverse direction when said back-rest is lowered.

4. A self-adjustable lamp structure for a bed having an adjustably tilttable back-rest and a stationary part adjacent thereto, said structure comprising a support adapted to be located in position adjacent the bed, a mounting movable on the support, a lamp carried by the mounting, a tubular element extending from the support, a push-pull wire within said tubular element connected with said mounting, one of said tubular elements and wire being adapted to be connected with said stationary part of the bed and the other thereof being adapted to be connected with the tilttable back-rest of the bed, whereby, when the lamp structure is applied to the bed for use, motion from the back-rest, as it is tilted into an altered position of adjustment, will be imparted to said mounting to reposition said lamp relative to the back-rest in its altered position.

5. A self-adjustable lamp structure for a bed having an adjustably tilttable back-rest and a stationary part, said structure comprising a support adapted to be located in position adjacent the bed, a mounting movable on the support, a lamp carried by the mounting, a tubular element extending from the support and adapted to be connected with one of the said back-rest and stationary part of the bed, motion transmitting means within the tubular element adapted to be connected with the mounting and with the other of said back-rest and stationary part of the bed, said motion transmitting means, when the lamp structure is applied to the bed for use, being adapted to be actuated by the back-rest upon the tilting thereof from one of its adjusted positions to another and, in turn, to act upon said mounting to reposition the lamp relative to the back-rest in its altered position of adjustment.
